[57] CLAIM

The ornamental design for an egg gathering hen's nest bottom, as shown and described.

DESCRIPTION

FIG. 1 is a front perspective view of a egg gathering hen's nest bottom, showing my new design;

FIG. 2 is a top plan view thereof;

FIG. 3 is a right side elevational view thereof, the left side being a mirror image of the right side shown;

FIG. 4 is an end elevational view thereof;

FIG. 5 is the end opposite that shown in FIG. 4; and,

FIG. 6 is a bottom plan view thereof.

FIG. 3

FIG. 4

FIG. 5

FIG. 6
